INTERMEDIATE AWNING BRACKET

Filed April 25, 1928

UNITED STATES PATENT OFFICE

EDWARD H. SCHANE, OF CLEVELAND, OHIO, ASSIGNOR TO THE FANNER MFG. CO.,
OF CLEVELAND, OHIO, A CORPORATION OF OHIO

INTERMEDIATE AWNING BRACKET

Application filed April 25, 1928. Serial No. 272,638.

This invention relates to a bracket and more particularly to a bracket adapted to be used as an intermediate support for an awning.

5 Large awnings require the use of one or more supporting members arranged intermediate of the usual end supporting brackets, such intermediate supporting members preferably being so constructed as to facilitate 10 the rolling and unrolling of the awning and to assist in the guiding thereof during such operation.

An object of the present invention is to provide a bracket of simple and economic 15 construction adapted to be used as an intermediate supporting bracket for an awning and one which is capable of being readily adjusted to be used with various sized awnings and which may be easily and securely fastened to the supporting structure.

20 Additional objects and advantages will become apparent from time to time as the specific description of a preferred embodiment progresses.

25 Such embodiment is illustrated in the accompanying drawing, wherein:

Fig. 1 is a top plan view of the bracket;

Fig. 2 is an end elevation thereof, certain 30 portions being broken away and shown in section; and

Figs. 3 and 4 are detailed sectional views of specific portions of the bracket.

The bracket comprises a main supporting member 1 preferably in the form of a substantially U-shaped casting, the web or attaching arm of which is provided with transversely extending teeth 2 on its rear side. The upper arm 3 of the supporting member is slightly arced upwardly and is provided 35 along one of its vertical side faces with a longitudinally extending channel 4, an opening 5 formed in its opposite vertical face communicating therewith for a purpose later to be set forth. The lower arm 6 extends perpendicularly outwardly from the web a greater distance than the arm 3 and has an intermediate enlarged portion 7 provided with a vertical longitudinally extending slot 8 communicating with a longitudinal channel 9 arranged on the upper side of the por-

tion 7 and in outstanding portions 10 at the upper sides of the end portions of the arm 6. The channel 4 of the upper arm and the channel 9 of the lower arm extend throughout the longitudinal lengths of their respective arms. 55

A member 11, curved to conform to the curvature of the arm 3 and of a size to slidably fit within the channel 4 therein, is adjustably secured to said arm within the channel by means of a bolt 12 passing through the opening 5 in the arm and through a longitudinal slot 13 in the member 11, a nut 14 being threaded upon the projecting end of the bolt to hold the parts in the desired position. The free end 15 of the member 11 is transversely reduced but vertically extended and of a general hook-shape configuration, being provided with separate spaced downwardly extending angularly disposed stop 60 projections or lugs 16 and 17. A transverse opening is provided in the end 15 at substantially the middle thereof, a bolt 18 extending therethrough serving to pivotally support a roller carrying member now to be described. 65

The roller carrying member is in the form of a substantially U-shaped yoke having spaced upwardly extending pivot lugs 19 arranged adjacent to the middle upper edge of the connecting arm 20 of the yoke and integral therewith and adapted to receive the end 15 of the member 11 therebetween and to be pivotally mounted upon the bolt 18. The outwardly extending arms 21 and 22 of the yoke fixedly support adjacent their outer ends a transversely extending roller supporting shaft or bolt 23 upon which a roller 24 is rotatably mounted. The stop lugs 16 and 17 serve the purpose of limiting the swinging pivoted movement of the yoke since 70 they engage the opposite faces of the arm 20 between the pivot lugs 19 upon a certain amount of movement of the yoke in opposite directions. 75

The arm 6 likewise adjustably supports a roller carrying member slidably mounted in the channel 9 therein. This latter member is substantially of the same width as the upper side of the arm 6 and is provided throughout its length with a downwardly ex- 80 85 90 95 100

tending rib 25 which slidably fits within the channel 9. The opposite ends of this member are enlarged to provide transverse hub portions 26 and 27 adapted to support roller carrying shafts 28 and 29, respectively. The shaft 28 extends through the outer hub 26, this shaft being relatively short and loosely mounted in the hub, while rollers 30, larger in size than the roller 24, are loosely mounted upon the opposite ends of the shaft between spacer washers 31 arranged intermediate the hub and rollers and similar washers 32 arranged on the shafts at the outer ends of the rollers and held against displacement therefrom by cotter pins 33 passing through an opening in the ends of the shaft. The rollers 30 are so positioned that when the bracket is in secured position the roller 24 will lie intermediate the ends of the rollers 30. The shaft 29 is considerably longer than the shaft 28 and is also relatively more tightly carried by its hub, the rollers 34 carried by said shaft being rotatably arranged on its outer ends so that the inner ends of such rollers are substantially in line with the outer ends of the rollers 30. The rollers 34 are held between washers 35, the inner pair of which are spaced from the hub by spacer sleeves 36 while the outer pair are held against axial displacement from the shaft by cotter pins 37. The roller carrying member for the arm 6 is adjustably secured in position by means of a bolt 38 extending through a vertically disposed centrally arranged opening 39 in the member between the hubs, the upper end of the opening being enlarged to accommodate the head 40 of the bolt, and through the slot 8 in the portion 7 of the arm 6. A nut 41 and washer 42, or some other suitable means, may be employed to secure the parts together.

In order to adjustably secure the bracket to a supporting wall 43 a plate 44 is employed, this plate being provided on one of its faces with transversely extending teeth or serrations 45 corresponding to the similar portions 2 of the web of the member 1 and adapted to be meshed therewith, and with a plurality of tangs or projections 46 on its opposite face adapted to engage in the supporting wall. A suitable self tapping stud bolt 47 extends through a slot 48 in the web of the member 1 and through an opening in the plate 44 into the supporting wall 43, a washer 49 being interposed between the web and the head of the bolt.

The bracket just described being secured to the supporting wall intermediate the end supporting brackets of an awning and adjusted vertically by means of its connection to the plate 44, with its rollers positioned inwardly or outwardly thereof as the case might require by means of their adjustable connection, and awning 50 wound upon a supporting shaft 51 rotatably supported in a

well-known manner by the end brackets may be supported at a plurality of spaced points by the rollers 30 and 34. When the awning is being lowered or raised the rollers do not hinder such movement but tend to assist the same as the cloth is smoothed out by such rolling engagement. The roller 24 carried by the pivoted yoke also serves to smooth out the cloth of the awning and to guide the same so that it will pass from and onto the shaft 51 in a predetermined direction because of the stops 16 and 17. 70 75

Although certain forms of adjustments and a certain arrangement and number of rollers have been shown and described it should be understood that the invention is not necessarily limited thereto, or to the exact form of the structural parts shown herein, since it is susceptible of such modifications and adaptations as fall within the scope 80 85 of the following claims.

Having thus described my invention, I claim:

1. A bracket adapted to be used as an intermediate bracket for an awning comprising a supporting member adapted to be connected to a supporting wall and having an outwardly extended arm, means associated with said arm and secured thereto to be adjusted toward or away from the supporting member, and rollers carried by said means adapted to engage an awning at a plurality of spaced points to support and guide the same. 90 95

2. A bracket adapted to be used as an intermediate bracket for an awning comprising a supporting member adapted to be adjustably connected to a supporting wall and having outwardly extended spaced arms, means associated with each of said arms and secured thereto to be adjusted toward or away from the supporting member, a swinging roller carrying member pivoted to one of such means, and a plurality of rollers carried by the other of said means, whereby an awning will be engaged by said rollers at a plurality of spaced points to support and guide the same. 100 105 110

3. A bracket adapted to be used as an intermediate bracket for an awning comprising a supporting member adapted to be adjustably connected to a supporting wall and having outwardly extended spaced upper and lower arms each of which is provided with a channel; an adjustable member arranged in the channel of the upper arm, a roller supporting member pivoted to the outer end thereof, an adjustable member associated with the channel in the lower arm, said last named member having a plurality of spaced parallel shafts, 115 120 125

and rollers rotatably mounted on said shafts at a plurality of spaced points.

4. A bracket adapted to be used as an intermediate bracket for an awning comprising a supporting member adapted to be ad- 130

justably connected to a supporting wall and having outwardly extended spaced upper and lower arms each of which is provided with a channel, an adjustable member arranged in the channel of the upper arm for adjustment longitudinally thereof having spaced lugs adjacent its outer end, a roller supporting member pivoted to the outer end of said first named member and limited in its movement by said lugs, a longitudinally adjustable member associated with the channel in the lower arm, said last named member having a plurality of longitudinally spaced parallel shafts, and rollers rotatably mounted 10 on said shafts at a plurality of spaced points.

5. A bracket adapted to be used as an intermediate bracket for an awning comprising a supporting member having outwardly extended spaced upper and lower arms, a roller 20 pivotally connected with the upper of said arms, a plurality of longitudinally spaced parallel shafts associated with the lower of said arms, said shafts being of different lengths, and rollers rotatably mounted on the 25 opposite ends of each of said shafts.

6. A bracket adapted to be used as an intermediate bracket for an awning comprising a supporting member having outwardly extended spaced upper and lower arms, a roller 30 connected with said upper arm, a pair of longitudinally spaced parallel shafts of different lengths associated with said lower arm, rollers rotatably mounted on the opposite 35 ends of each of said shafts, the roller connected with said upper arm lying above and intermediate the outer ends of the rollers arranged upon the opposite ends of one of said shafts and the rollers rotatably mounted upon opposite ends of the other of said shafts being located outwardly of the outer ends of the rollers upon said first mentioned shaft of the above mentioned pair of shafts.

In testimony whereof, I hereunto affix my
signature.

EDWARD H. SCHANE.
